UNITED STATES PATENT OFFICE.

DANIEL W. PEERY, OF CARNEGIE, OKLAHOMA.

ROAD CONSTRUCTION.

1,334,790.

Specification of Letters Patent. Patented Mar. 23, 1920.

Application filed June 7, 1919. Serial No. 302,438.

To all whom it may concern:

Be it known that I, DANIEL W. PEERY, a citizen of the United States, residing at Carnegie, in the county of Caddo and State 5 of Oklahoma, have invented new and useful Improvements in Road Constructions, of which the following is a specification.

This invention relates to road constructions and comprehends the provision of 10 spaced parallel tracks or surfaces of relatively hard material over which the wheels of a vehicle travel, and an intermediate track or surface of suitable material to afford a soft and sound footing for the animals drawing the vehicle.

The nature and advantages of the invention will be better understood when the following detailed description is taken in connection with the accompanying drawing, 20 the invention residing in the construction, combination and arrangement of parts as claimed.

In the drawing forming part of this specification, like numerals of reference indicate 25 similar parts in the several views and wherein:

Figure 1 is a fragmentary plan view of a road constructed in accordance with my invention.

30 Fig. 2 is a sectional view taken approximately on line 2—2 of Fig. 1.

Fig. 3 is a detail view of one of the combined curbs and track blocks.

In carrying out my invention I construct 35 a road including a center track or surface indicated at 10, and composed of hard material of any suitable character such as concrete or the like. At the opposite sides of the road I make use of the combined track 40 and curb blocks indicated in Fig. 3, wherein the curb proper is indicated at 11 and the track portion at 12. Manifestly, the track proper of each block projects horizontally from the curb at an appropriate point 45 in the height thereof and in constructing the road these blocks are arranged end to end with that portion of the curb 11 projecting beneath the track 12 embedded in the surface. It is of course to be under-

50 stood that the combined curb and track blocks may be constructed from any suitable material, the track 12 preferably of the same material, as that composed in the makeup of the track 10, and that the blocks 55 may vary in dimensions without departing

from the spirit of the invention. With a view of more securely holding the combined curb and track blocks together when arranged end to end, each block is provided with an eye or loop 14 projecting from one 60 end thereof and a wire tie 15 projecting from the opposite end, the wire tie 15 being arranged to be passed through the eye 14 of the adjacent block and subsequently tied in any suitable manner. The intervening space between the center track 10 and the side tracks 12 is filled with clay, gravel or broken stone or other suitable material to provide a soft and sound footing for the animals drawing the vehicle. This relatively 65 soft track is indicated at 17. If found necessary, each of the side tracks 12 may be secured to the adjacent edge of the center track 10 by means of a wire tie 18, which of course would be embedded in the 70 relatively soft track 17. This tie however, would only be needed on hills or grades.

It is to be further understood that in constructing a road, certain of the combined curb track blocks are properly curved to 80 conform to the curvature or turns of the road. As shown, the side tracks 12 are relatively narrow compared to the similar dimension of the center track, the latter being of a sufficient width to permit vehicles to 85 pass over the road in opposite directions, it being borne in mind that the wheels of the vehicle pass over one of the side tracks 12 and the center track 10, as the relatively soft track 17 is to be only traversed by animals. 90 As in the usual construction of roads, the road bed is to be slightly crowned so that the water falling upon the road would run to the opposite side into the gutters, and at an appropriate point the combined curb and track 95 blocks are provided with openings 19 for drainage purposes.

I desire to have it understood that what is herein shown and described is merely illustrative of the preferred embodiment of the 100 invention, to which I do not limit myself, and that such changes in such as material, dimensions, and configuration of parts employed may be resorted to when desired as fall within the scope of what is claimed.

What I claim is:—

1. A road construction including a center track of hard material, combined curb and track blocks arranged at the opposite sides of the road, the track portions of said block 110

- projecting from the latter at an appropriate point in their height and spaced from the center track, tie rods wholly embedded in the road and arranged to connect the tracks of said blocks with the center track, and means to connect the adjacent ends of the blocks together, and said blocks at the point of juncture between the track and curb being provided with a plurality of drain openings. 5
- 10 2. A road construction comprising a center track of hard material, a combined track and curb block arranged at the opposite sides of the road to provide an intermediate track of soft material, the track portions of 15 said blocks projecting from the latter at an appropriate point in the height thereof, loops projecting from the longitudinal edge of each track portion of said block, tie rods terminally embedded in the center track, 20 and having their opposite corresponding ends designed to receive said loops whereby the said spaced tracks are connected together, and means carried by the blocks for connecting the adjacent ends of the blocks together. 25
3. A road construction including a center track of hard material, combined curb and track blocks arranged at the opposite sides of the road and spaced from the center track to provide intermediate tracks of soft material, the track portions of said blocks projecting from the latter at appropriate points in their height, means for connecting the spaced tracks together, the track portion of each block being cut away to provide a recess at one end, a tie rod passed longitudinally through said track portion and formed to provide an eye arranged in said recess, the opposite end of said rod projecting from the block, and adapted to be threaded through 30 said eye carried in the pocket of the adjacent block, whereby said blocks are secured together. 35
- 40

In testimony whereof I affix my signature.

DANIEL W. PEERY.
